BATTERY IGNITION SYSTEM

Filed March 26, 1929

UNITED STATES PATENT OFFICE

CURT FREDERICK REIS, OF CHICAGO, ILLINOIS, ASSIGNOR TO EXCEL MAGNETO CO.,
OF CHICAGO, ILLINOIS

BATTERY IGNITION SYSTEM

Application filed March 26, 1929. Serial No. 350,029.

This invention relates to a battery ignition system, and in particular to a combined structure involving an interrupter, an induction coil, and a rotary distributor.

5 An object of this invention is to devise an ignition system in which the induction coil is incorporated in the structure of the rotary distributor, thereby eliminating the high tension connection between the separate induction coil and the rotary distributor.

10 I propose to incorporate the induction coil of my ignition system into the removable head on the rotary distributor. By such an arrangement I eliminate all extra connections 15 from the induction coil to the distributor and timing interrupter, leaving only one connection between the energizing battery and the distributor head.

I propose also to embed the induction coil 20 within the insulating material forming the removable head of the rotary distributor, and thereby avoid leakage of the high tension current which would otherwise occur where the induction coil is separate from the rotary distributor. The construction of my invention 25 also has the advantage of being water and dust proof.

I further propose to incorporate within the structure of the rotary distributor head a resistance in series with the battery circuit to 30 properly limit the current.

35 My invention is illustrated in the accompanying drawing in which Fig. 1 is a vertical sectional view taken through the axis of the combined ignition apparatus;

Figure 2 is a fragmentary sectional view of the distributor head and part of the rotary distributor taken at right angles to the section in Figure 1 through the vertical axis;

40 Figure 3 is a view of Figure 1 taken along the line 3—3.

Referring to Figure 1, the rotary distributor and interrupter are housed within a casing A which is preferably formed of cast metal. The lower end of the housing is provided with a tubular bearing extension A' which is journaled in a bearing formed on the engine casing or frame as is well understood. Journaled within the extension A' is an operating shaft B which is driven from the motor

by suitable gearing. The upper end of shaft B is provided with an automatic spark advance mechanism C of usual construction, and the shaft extension B' carries at its upper end an interrupter cam C and a rotary 55 distributor disc E. The rotary disc E is located in the upper open end of casing A, and is provided with a central contact button F and a rotary contact button G located near its periphery, the two contact buttons being 60 connected together by a suitable connection.

The upper end of casing A is closed by a removable distributor head H made of molded bakelite or other suitable insulating material. This distributor head has formed 65 thereon suitable bosses 4, 5, 6, 7 etc., having the usual high tension terminals embedded therein. These high tension terminals are suitably connected to corresponding stationary distributor contacts J located on the bottom face of the distributor head. Embedded 70 within the distributor head H is an induction coil 8, the primary winding of which is indicated at 8a and the secondary winding at 8b.

The induction coil 8 is provided with a laminated iron core 9 which is also embedded within the head H, and is in the form of an inverted U. The magnetic circuit for the core 9 is completed through two arcuate laminated iron core members 10a and 10b 75 located in the upper rim of the casing A. These core members are preferably incorporated in the casing structure by casting the casing A around the core members after they have been properly located. Referring to Fig- 80

ure 3, it will be seen that a considerable gap exists between the ends of the two core members, and the ends of core 9 are located adjacent these gaps. The core 9 is of less width than the gaps between the core members 10a 85 and 10b, thereby leaving a desired amount of air gap in the magnetic circuit for best operation of the induction coil. Normally, core 9 would not appear in Figure 3, but it has been shown in dotted lines for the purpose of showing its position with respect to the gaps between cores 10a and 10b.

One terminal of the primary winding 8a is connected to the interrupter 11 by a wire 12, and the other terminal of the primary wind- 100

ing is connected to a resistance 13 embedded in the upper central part of the distributor head H. The remaining terminal of resistance 13 is connected to the battery terminal 14, to which is connected an energized battery Ba. One end of the secondary winding 8b is suitably grounded, and the other end is connected to a central contact button 15 located in the lower face of head H and operating with central contact button F on the distributor disc E.

Operation of the invention is as follows: Rotation of the drive shaft B serves to operate the interrupter 11 through the action 15 of the cam D in a well-known manner. This interrupts the primary circuit at timed intervals, and induces high voltage impulses into the secondary winding. Rotation of the distributor disc E effects the successive distribution 20 of the high tension impulses to the different ignition circuits connected with the stationary contacts J on the distributor head. The resistance element 13 embedded in the distributor head serves to properly limit the maximum current which flows in the primary winding. The spark may be advanced or retarded in the usual manner by shifting the casing A about its vertical axis by usual control devices connected to extension A'' on 25 casing A.

From the foregoing it will be noted that I have devised an arrangement in which all the elements involved in a battery ignition system (except the battery) are incorporated 30 in a single unitary structure.

What I claim as new and desire to secure by Letters Patent is:

1. A distributor head comprising a body of molded insulating material having embedded 40 therein an induction coil, said coil being provided with an angular core the two ends of which are exposed at spaced points on the flat bottom face of said distributor head.

45 2. In an ignition apparatus, the combination of a rotary distributor casing, a cover therefor comprising a body of insulating material having embedded therein an induction coil, said induction coil being provided with an open magnetic core of substantially U-shape, and means embedded in said casing 50 for completing the magnetic circuit of said core.

3. In an ignition apparatus, the combination 55 of a rotary distributor casing, a cover therefor, an induction coil embedded in said cover and provided with an open magnetic core, and a magnetic element embedded in said casing for closing the magnetic circuit of said core.

4. In an ignition apparatus a rotary distributor casing comprising an open ended cylindrical casting having embedded in the 60 rim thereof two arcuate magnetic cores with

magnetic gaps intermediate the ends of said cores.

5. In an ignition apparatus, the combination of a rotary distributor casing comprising an open ended cylindrical casting having embedded in the rim thereof two arcuate magnetic cores with magnetic gaps intermediate the ends of said cores, a cover for said open ended casting comprising a body of insulating material having embedded therein an induction coil, said coil being provided with a magnetic core the ends of which terminate adjacent the magnetic gaps between said magnetic core members.

6. The combination with a distributor casing and a magnetic element embedded in said casing, of a distributor head having an induction coil embedded therein, said coil having a U-shaped core magnetically associated with the magnetic element in said casing to 85 form a substantially closed magnetic circuit.
